His Attorney

UNITED STATES PATENT OFFICE

RUDOLPH L. HANSON, OF FREWSBURG, NEW YORK, ASSIGNOR TO JAMESTOWN METAL DESK COMPANY, OF JAMESTOWN, NEW YORK, A CORPORATION OF NEW YORK

FILE DRAWER

Application filed July 16, 1931. Serial No. 551,163.

This invention relates to an improvement in file drawers and more particularly to the drawer head thereof.

The preferred embodiment of the invention discloses a file drawer head in which a compartment is formed. A key-controlled door is provided in one of the walls of the head, the opening of which gives access to the manipulation of one or more card file retaining rods.

In certain kinds of offices it has been found desirable to provide a file cabinet, the drawer structure of which is such as to prevent the unauthorized removal and at the same time permit examination of file cards, folders, papers, etc. Heretofore, this has not been possible inasmuch as the end of the rods, by which the cards are retained, projected beyond the drawer head and could be readily withdrawn. The present invention is designed to make use of the space between the inner and outer drawer head walls for locating the head of one or more card retaining rods. A key controlled door formed in one of the walls of the drawer head gives access to the removal or insertion of these rods and the subsequent removal of the contents of the drawer.

The principal object of the invention lies in the provision of a drawer head having a door formed in one wall thereof and by which access to the interior of said head may be had.

Another object of the invention lies in the provision of a drawer head having a compartment adaptable for receiving the ends or knobs of file card retaining rods and suitable means for preventing unauthorized removal of said rods.

Other and further objects of the invention will be more clearly understood from a consideration of the following specification which is taken in conjunction with the accompanying drawing, and in which

Fig. 1 is a fragmentary perspective view of a cabinet, showing a partly opened drawer, embodying one form of this invention;

Fig. 2 is a vertical sectional view of the drawer head shown in Figure 1 with the file card retaining rod in place;

Fig. 3 is a vertical sectional view showing the drawer head door opened, and the rod removed to permit withdrawal of any of the file cards; and

Fig. 4 is a rear view, partly broken away, showing the location of the door which is mounted in the drawer head.

Referring to the drawing, one modification of the invention is shown in a file drawer, generally indicated by the reference numeral 10. The drawer 10 is mounted in a file cabinet 11 and comprises a drawer head 12, side walls 13 and bottom wall 14.

The drawer head 12 is comprised of inner and outer plates 16 and 17. The outer plate 17 is formed on all four sides with rearwardly and inwardly projecting flanges, the upper flange 18 being shorter than the bottom flange 19, the purpose of which is to accommodate the inner plate 16. The inner plate 16 is formed with inwardly projecting side and bottom flanges 23 and 24 respectively. A flange along the upper edge 25 of this plate corresponds to the side and bottom flanges and continues in a vertical flange 26 which terminates in an acute angle flange 27. Flanges 25 and 26 form a shoulder which, when the plates 16 and 17 are joined, engages the flange 18 of the outer plate. Flange 27 of the inner plate acts as a spacer. The bottom flange 24 of the inner plate 16 may be permanently secured to the bottom of the drawer 14 in any desired manner. It will be noted that a chamber or compartment 29 is formed within the drawer. It will also be noted that a compartment such as provided in the disclosed structure generally results from standard drawer head construction and, therefore, the particular assembly of the plates 16 and 17, the size of the compartment 29, and the drawer pull 30 and its means of attachment form no part of this invention and will not further be discussed.

The outer plate 17 is cut to provide a rectangular opening 32 for a door 33. The door is terminated along its lower edge by a rearwardly and inwardly turned flange 34. One or more hinges 36 connect the flange 34 of the door with the under face of the bottom wall 14 of the drawer, being welded,

screwed or otherwise suitably fastened. A lock 36' is mounted on the inner face of the door, the head 37 of which projects through the plate 17. A stop plate 38, secured to the inner face of the plate 17, projects slightly beneath the upper edge of the door opening 32 and thus limits the inward movement of the door. That portion of the plate 38 which projects into the opening 32 terminates in a horizontal flange 39 with which the bolt 40 of the lock may be engaged.

Secured to the inner plate 16 is a reinforcing plate 42. A threaded opening 43 is made through plates 16 and 42. A file card retaining rod 44 projects through the opening 43 into the space within the body of the drawer 10. The outer end of the rod 44 terminates in a knurled head 45 on which a threaded portion 46 is formed, which engages the threads of the opening 43. The rod 44, when mounted in the drawer, as indicated in Figure 2, prevents removal of any of the cards 47. By unlocking the door 34, and allowing it to drop down to the position indicated in Figure 3, the head 45 of the rod is exposed to view and the rod may be disengaged from the plates 16 and 42 and withdrawn from the drawer, thus permitting removal of any of the cards 47. It is pointed out that the compartment 29 is not of unusual depth nor is the head 45 of the rod especially sized to fit within the compartment. The drawer head structure and the rod, being of standard construction, materially aid in reducing the cost of producing a drawer head equipped with a compartment door and lock as and for the purposes above stated.

Although applicant has shown but one modification of his invention, he does not intend to be limited thereto since it is obvious to those skilled in the art that other modifications or adaptations may be made without departing from the spirit and scope of the invention as set forth in the hereunto annexed claims.

Having thus set forth my invention what I claim as new and for which I desire protection by Letters Patent is:

- 50 1. In a file drawer, a drawer head having inner and outer connected plates forming a compartment, and a door formed in one of said plates and giving access to said compartment.
- 55 2. In a file drawer, a drawer head having inner and outer connected plates forming a compartment, a door formed in one of said plates and hinged to the bottom wall of said drawer, said door giving access to said compartment.

60 3. In a file drawer, a drawer head having inner and outer connected plates forming a compartment, a door formed in said outer plate and partly defining the lower edge thereof, hinge means joining said door to the

bottom wall of said drawer, said door giving access to said compartment.

4. In a file drawer, a drawer head having spacedly joined inner and outer plates forming a compartment, a door in the outer of said plates, a hinge joining said door to the bottom wall of said drawer, a card retaining rod projecting into said compartment through the inner of said plates, said door giving access to said compartment and said rod.

5. In a file drawer, a drawer head having inner and outer connected plates forming a closed compartment, walls defining an opening in said outer plate, a door closing said opening, and a lock in said door engageable with said outer plate whereby to control access to said compartment.

6. In a file drawer, a drawer head having a compartment, a card retaining rod terminating in said compartment, walls defining an opening in one face of said head, a door closing said opening and operable to give access to said compartment and the removal of said rod.

7. In a file drawer, a drawer head having a compartment, a card retaining rod in said drawer, said rod being terminated by a knob lying in said compartment, and a door in one face of said head, said door being operable to give access to said compartment and said rod.

8. In a file drawer, a drawer head having a compartment, a card retaining rod in said drawer, said rod being terminated in said compartment, walls defining an opening in one face of said head, a hinged door closing said opening, and lock means on said door for controlling access to said compartment and the removal of said rod.

9. In a file drawer, a drawer head having inner and outer connected plates forming a compartment, a card retaining rod in said drawer, said rod terminating in a knob in said compartment, walls defining an opening in the outer of said plates, a hinged door closing said opening, a plate secured to said outer plate above said opening, a key controlled lock in said door engageable with said plate, said lock preventing manipulation of said door to gain access to said rod.

10. In a file drawer, a drawer head having inner and outer plates forming a closed compartment, and operable means in one of said plates giving access to said compartment.

In testimony whereof I have affixed my signature.

RUDOLPH L. HANSON.
